SPRAYING NOZZLE

Filed April 12, 1927

Patented May 14, 1929.

1,713,260

UNITED STATES PATENT OFFICE.

EDWARD F. CHANDLER, OF BROOKLYN, NEW YORK.

SPRAYING NOZZLE.

Application filed April 12, 1927. Serial No. 183,099.

- This invention relates to atomizing and spraying apparatus, and more particularly refers to improvements in the construction of oil burners and other spraying devices.
- 5 The primary object of this invention is to provide a novel and improved construction of nozzle intended for use in connection with a liquid to be delivered by said nozzle and a fluid acting as a carrier or as an atomizing medium therefor, whereby the pressure of the latter fluid is converted into velocity at a point very close to the nozzle outlet, so that the loss of velocity due to frictional resistance is reduced to a minimum.
- 10 Another object is to provide in a nozzle or oil burner, novel and improved means for stratifying the atomizing medium used, in order to duplicate the effect obtainable in this respect by the provision of a plurality 15 of outlets for the same such as made in certain types of burners, yet, simplifying the construction of the nozzle, at the same time improving its operating efficiency.
- 15 A further object is to provide in a nozzle where a liquid to be sprayed is delivered to the tip of the nozzle, partly or totally by virtue of suction exerted by carrying or atomizing medium, an improved arrangement of outlet whereby the suction exerted by the carrying or atomizing medium may be increased by a suitable design of the outline of 20 said outlet.
- 20 A still further object is to provide a spraying nozzle of a novel and improved construction, which is composed of relatively few parts, permitting easy cleaning and inspection of the working parts of the nozzle without entailing the necessity of disconnecting it from the source of fluid supply.
- 25 Other objects and advantages of the present invention will more fully appear as the description proceeds and will be set forth and claimed in the appended claims.
- 30 The improvements forming the object of the present invention are particularly adapted for use in connection with nozzles or burners of the type described in another patent application co-pending herewith, Serial No. 690,758, where the liquid to be delivered 35 or atomized is caused to travel over the surface of a conical valve element, as a constantly thinning film until the periphery is reached, where it is blown from the knife like edge of the valve in a nebulous spray.
- 40 In a nozzle of this type, the proper velocity in an outward direction is imparted to the fluid film before the edge is reached, by virtue of the deflecting action of the distributing surface of the valve, upon the fluid impacting thereagainst, and the action of the 45 atomizing agent directed against said surface, said direction being that of the distributing surface; so that the spray is directed in continuation of said surface at the moment of leaving it. There is no tendency or 50 cause for any part of the liquid to remain adherent to the surface, and to eventually drip therefrom and its discharge velocity may be sufficiently low to permit of practically perfect combustion at the normal rate of 55 flame propagation.
- 55 The main features of my invention are to a certain extent independent of the means used for creating the spraying pressure. In some types of burners steam is used for atomizing the fuel, while in other types, compressed air is used; in other burners of the so called mechanical type, the fuel is pumped from the storage tanks and forced under pressure to the burner, from which it issues 60 through a small orifice in atomized form.
- 65 In still another type of burners, the fuel is delivered under pressure and an atomizing medium is also used at the same time, assisting the action of the pressure in the 70 atomization of the fuel. Any one of these methods may be employed in connection with my device, although I prefer to use as an atomizing medium, air compressed under 75 relatively low pressure, because steam represents a waste of from 3% to 7%, and a proportionate increase in the oil consumption.
- 80 The drawings refer to nozzles of the type especially suited for oil burning purposes, but as stated before my invention may be applied broadly in connection with nozzles of 85 a different character. Referring to said drawings:
- 85 Fig. 1 is a fragmentary sectional elevation of a burner embodying my invention; 90
- 90 Fig. 2 is a cross sectional view through line 2-2 of Fig. 1; 95
- 95 Fig. 3 is a fragmentary sectional elevation of the outer end portion of a similar burner, having outlets with a slightly different outline; 100
- 100 Fig. 4 is a detail sectional elevation illustrating the construction of the tip end of the burner shown in Fig. 1; and 105
- 105 Fig. 5 is a similar view illustrating the tip 110 end of a burner having outlets of a slightly different design.

Referring to Figs. 1, 2, 4, 10 designates a body or frame provided with an oil inlet 11, leading to a central chamber 12, inwardly recessed from a chamber 13 of a larger diameter to which leads a conduit 14 for the atomizing medium.

The central chamber is extended to the tip end of the burner by means of a tubular member 15, screwed into the inner surface 16 of chamber 13 and outwardly extending therefrom.

In a similar manner, chamber 13 is extended to the tip end of the burner by means of another tubular member 17, screwed on to the outer end 18 of said body or frame and extending outwardly therefrom, coaxially with tubular member 15. The outer end of said tubular member or casing 17 is threaded so that an end bushing or collar member 19 can be mounted thereon, forming a continuation of chamber 13.

In this manner, chamber 12 forms a passage for the fuel, and chamber 13 forms a passage for the atomizing medium used, for instance compressed air.

In order to obtain a good operating efficiency, it is desirable to cause the atomizing medium to issue from the burner at a fairly high velocity, but at the same time the use of high pressures is to be avoided, if possible.

In the burners described in my other patent application above referred to, a relatively large volume of atomizing medium is delivered to the burner as compared to the volume of liquid to be atomized, this being a particularly desirable condition in the case of oil burners because, if air under pressure is used as the atomizing medium, this air will also intimately intermingle with the fuel particles and will eventually assist their combustion.

However, as stated, the air should be delivered at a fairly high velocity in order to impart the necessary velocity to the fuel, and therefore, a relatively large total area for the passage of the air is obtained by providing two or more passages therefor, each having a relatively restricted area and causing therefore, the air to pass therethrough at an increased speed. The air passages thus provided are obtained by the use of coaxial tubular members, forming annular passages, all leading to the tip end of the burner and delivering the air in different concentric strata, each having a relatively high velocity.

In the present case, I obtain a parallel effect, merely by restricting and multiplying the air outlets at the tip end of the air burner without the use of a relatively long tubular member interposed between the inner and the outer tubular members mentioned.

The desired result is obtained by inserting an end bushing member 20, between the tip end of tubular member 15 and bushing or col-

lar 19. Said bushing member 20 is provided with radial projections 21, outwardly extending therefrom, adapted to position the bushing so it will remain coaxial with members 15, 17, 19, said bushing 20 being retained in position by clamping said projections 21 between the end surface of tubular member 20 and the inner recessed surface 22, of member 19.

The burner outlet proper is composed of outlet 23 at the outer end of member 15, and annular outlets 24, 25, between said member 15 and bushing 20 and between said bushing 20 and bushing 19, respectively.

The burner outlet is controlled by means of a conical valve 26, carried at the outer end of a valve stem 27, extending centrally of member 15 throughout its entire length, and projecting at the rear through body or frame 10. A tight packing of the passage of the stem through the rear end of the body or frame 10 is assured by providing a stuffing box at said end, comprising a packing 28 compressed within its chamber by means of a pressure member 29, having a threaded portion 30 screwed onto the rear end of said body or frame compressing said packing.

Said pressure member 29 is provided with a key or pin 31, projecting into a key slot 32, formed longitudinally of the valve stem, so that the valve stem is restrained from rotating in relation to the said pressure member.

The inner end of the valve stem is threaded as shown at 33, and carries a nut member 34, by means of which axial movement of the valve stem can be produced in one or the other direction for the purpose of valve adjustment.

The correct alignment of the valve stem is insured at the outer end by means of a plurality of radial extensions 35, registering with the inner surface of member 15.

The outer ends of members 15, 20, 19, are outwardly beveled so as to register with the surface of valve 26 when the valve is closed; furthermore, the outer diameter of collar or bushing 19 is preferably equal to or slightly larger than the outer diameter of the cone valve, so that when the valve is closed, the base or outer surface 36 of said valve is flush with or is entirely within the edge of said collar or bushing. The arrangement of the outer ends of members 15, 20, 19, described, is referred to in the claims by reciting that the tip ends of said members are in "conical alignment" with one another, this being intended to convey the idea of a conical surface formed by spaced annular elements parallel to the surface of the valve.

The outer surface 36 of the valve is at right angle to its axis so that the valve terminates with a knife-like edge 37, adapted to eventually break up the film of liquid to be atomized as it spreads outwardly upon the conical sur-

face of the valve, gradually thinning out and eventually reaching said edge.

It will be observed that by virtue of this construction, the central passage 23 and the 5 annular passages 24, 25, have surfaces parallel with the axis of the valve stem, directing the fluids passing therethrough against the surface of the valve at a relatively wide angle to the direction of said surface.

10 At the same time, it will be observed that as the valve is outwardly displaced, it will form annular conical passages between the beveled ends of members 15, 20, 19, and its own conical surface, said annular conical passages 15 forming a continuation, respectively of passages 23, 24, 25. Due to the comparatively easy bend that the fluids or liquids have to follow in order to issue from the axial into the conical passages, there is practically no 20 loss of velocity taking place due to the impact of these liquids against the surface of the valve, and there is in fact rather a tendency to increased velocity due to a Venturi effect taking place when the conical passages are 25 narrower than the cylindrical passages, so that very even and efficient operation of the burner results. This is due to the fact that absence of impact causes the fuel to be atomized to be evenly and smoothly distributed 30 upon the surface of the valve without any eddy or break up action taking place before the said fluid reaches the edge of the valve.

Various positions of the valve whereby such an effect may be obtainable are illustrated in Fig. 3, where 15' designates the 35 inner tubular member, 17' the outer tubular member, 19' the outer collar or bushing member, 20' the inner bushing member and 26', 26' the valve in two different positions. As 40 shown in said Fig. 3, the beveled edges of members 15', 20', 19', are in conical alignment with one another being adapted to register with the conical surface of valve 26'.

The Venturi effect due to the construction 45 described however, can be further intensified by outwardly beveling part or all of the end surfaces of the bushing members at a greater angle than the angle of the valve surface. For instance, in the arrangement of Fig. 1, 50 also shown in an enlarged scale in Fig. 4, the inner portion 38 of the end surface of member 20, is beveled to register with the conical surface of the valve, but its outer portion 39 is beveled at a great angle, thus providing 55 a true stream line effect.

In a similar manner inner portion 40 of the end surface of member 19 is beveled to register with the conical surface of the valve, while its outer portion 41 is beveled at a 60 greater angle, the angular difference between the inclination of the two resulting conical surfaces being designated by α .

The Venturi effect thus obtainable is desirable especially when the suction exerted 65 by the carrying or atomizing medium is

mainly relied upon to cause the liquid to be delivered or atomized to issue from the tip of the burner at the desired velocity. In the case illustrated, the Venturi effect is especially desirable in connection with the intermediate passages, that is, the passage for the carrying or atomizing fluid which is closer to the central passage for the liquid to be delivered or atomized; the greatest suction being needed at said point.

On the other hand, in many cases it may be preferable to cause the entire end surface of the upper member 19 to be parallel to or to register with the conical surface of the valve, because one of the objects of said surface is to guide the fluid film up to the very edge of the valve, preventing the same from leaving the surface of the valve before the edge is reached.

In Fig. 5, I illustrate another arrangement 85 whereby it is possible to increase the natural Venturi effect of the burner, the arrangement being applied to the end surface of the inner bushing member 20'. In said drawing, 42 designates the conical surface of the valve, 43 90 the end surface of the upper bushing member 19', which is shown adapted to register with the said conical surface of the valve, and 44 designates the end surface of the inner bushing member 20', said surface being beveled in 95 its entirety at a greater angle than the conical surface of the valve, the angular difference between the inclination of the two surfaces being indicated by β .

It will be observed that by virtue of the 100 arrangements described, the area of the passage for the carrying or atomizing fluid is restricted at a point close to the outlet in order to increase the velocity of flow, without 105 restricting the range of action of the fluid flow; this result being obtained by sub-dividing the outlet in a number of passages adapted to stratify or otherwise subdivide the fluid flow in a number of streams, practically covering the same amount of surface as covered 110 by the main passage.

It is obvious that while only two annular passages formed in this manner are shown in the drawing, the number thereof may be increased; it is also obvious that the same 115 principle may be extended to the passage through which the fluid to be delivered or acted upon issues from the nozzle, and that the relative positions of the passage for the liquid delivered or atomized and that for the carrying or atomizing medium may be 120 inverted if desired.

The beveling of part or all of the end surfaces at an angle greater than that of the surface of the valve may also be adopted in connection with burners composed of a plurality of tubular members extending for the entire length of the burner such as described in my other patent application above referred to.

This and other details of the construction 130

of my device may vary to a certain extent from those shown in the drawing without departing from the spirit of my invention and therefore, I reserve myself the right to carry 5 my invention into practice in any way or manner which may enter fairly into the scope of the appended claims.

A purpose of this invention is to afford an economical and efficient means for projecting 10 a spray of highly comminuted, uniformly disposed matter, regardless of its initial state. Obviously the matter, to permit of delivery to the device must be in condition to flow. It may be a suitable liquid or it may be a fluid 15 such as powdered coal. Accordingly, the use of the word liquid in the specifications and claims is not to be taken as a limitation in this respect. Also the use of the word atomizer is not to be construed as a limitation. 20 While it may not be common usage to refer to atomization of a fluid such as powdered fuel, coal, etc., the effect produced, and the result accomplished is similar in this case.

I claim:

- 25 1. In a device of the class described the combination with a passage for a liquid and a fluid chamber concentric thereto, said chamber extending to a point close to the outlet end of said passage, of means forming a plurality of circumstantial series of outlets for said chamber, adjacent the outlet of said passage, the total area of said outlets being less than the area of said chamber, so as to cause an increase in the velocity of fluid forced therethrough, and an axially adjustable valve 30 adapted to control said outlets.
- 35 2. In a device of the class described, the combination of a tubular member forming a passage for a fluid, another tubular member external thereto, and coaxial therewith forming a fluid chamber extending to a point close to the outlet end of said passage, a collar member secured to the tip end of said outer tubular member, a bushing member interposed between the outlet end of said passage and said collar member adapted to be held in position by said collar member, the tip ends of said inner tubular member, bushing member and collar member 40 being in conical alignment with one another and defining in part an outwardly spreading conical chamber and forming a valve seat, an axially adjustable conical valve adapted to 45 coact with said seat to control the passages formed by said tubular bushing and collar member.
- 50 53 3. In a device of the class described, the

combination with an axially adjustable conical valve, of a plurality of tubular members coaxial with said valve forming a plurality 60 of concentric passages directed against the conical surface of said valve, the ends of said tubular members being formed to provide a seat for the conical surface of said valve, the end surface of part of said tubular members, spreading out at an angle greater than the inclination of the conical surface of said valve. 65

4. In a device of the class described, the combination with an axially adjustable conical valve, of three tubular members coaxial therewith, the outer ends of said tubular members being formed to provide a seat for the conical surface of said valve, and the end 70 surface of the intermediate tubular member spreading out at an angle greater than the 75 inclination of the conical surface of said valve.

5. In a device of the class described, the combination of a tubular member forming a passage for a fluid, another tubular member 80 external thereto, and coaxial therewith forming a fluid chamber extending to a point close to the outlet end of said passage, a collar member secured to the tip end of said outer tubular member, a bushing member interposed between the outlet end of said passage and said collar member adapted to be held in 85 position by said collar member, the tip ends of said inner tubular member, bushing member and collar member being in conical alignment with one another, and forming an outwardly spreading conical chamber, and an axially adjustable conical valve adapted to fit 90 within said conical chamber and to control the passages formed by said tubular bushing 95 and collar member, the end surface of some of said members spreading out at an angle greater than the inclination of the conical surface of said valve.

6. In a device for projecting an agent in a 100 divided and uniformly dispersed state, the combination with a passage for said agent, and a chamber concentric thereto for a fluid for projecting said agent, said chamber extending to a point close to the outlet end of 105 said passage, of means forming an outlet having a restricted area for said chamber, adjacent the outlet of said passage, without deflecting the direction of flow therethru of the agent or the fluid, in relation to the axis of 110 said chamber and passage, and an auxiliary adjustable valve adapted to control said outlets.

EDWARD F. CHANDLER.
